UNITED STATES PATENT OFFICE.

AARON L. MANN, OF GRAND RAPIDS, MICHIGAN.

LIFTING JACK.

1,404,455.

Specification of Letters Patent. Patented Jan. 24, 1922.

Application filed December 5, 1919. Serial No. 342,665.

To all whom it may concern:

Be it known that I, AARON L. MANN, a citizen of the United States, residing at Grand Rapids, in the county of Kent and 5 State of Michigan, have invented certain new and useful Improvements in a Lifting Jack, of which the following is a specification.

My invention relates to improvements in lifting jacks and more particularly to jacks 10 provided for use in connection with automobiles, wagons, and similar vehicles.

The primary object of the invention lies in the provision of a lifting jack that is strong and durable in construction, which 15 is capable of use with various vehicles irrespective of the difference between their axle and the ground, and which may be collapsed into a very small compass when not in use for convenience in transportation.

20 A further object of the invention is to produce a device of the above character which is collapsible in structure, easy to assemble for use when desired, and which when assembled will be braced in a rigid position, thus assuring the proper operation of 25 the device.

Other objects and advantages of the invention will be apparent during the course 30 of the following description.

35 In the accompanying drawings, forming a part of this specification and in which like numerals are employed to designate like parts throughout the same,

Figure 1, is a side elevation of a lifting 40 jack embodying my invention showing the parts arranged in operative position;

Figure 2, is a horizontal sectional view on line 2—2 of Figure 1;

Figure 3, is a vertical sectional view on 45 line 3—3 of Figure 1;

Figure 4, is a perspective view of the shoe used in connection with my invention;

Figure 5, is a perspective view of the base plate;

Figure 6, is a side view showing the relative position of the parts when collapsed;

Figure 7, is a perspective view of the lifting lever;

Figure 8, is a perspective view of the 50 parts in detail used in connection with the lifting lever; and

Figure 9, is a detailed perspective view of one of the bearing blocks.

In the drawings, wherein for the purpose 55 of illustration I have shown a preferred embodiment of my invention, the numeral

5 designates the base member which is preferably formed from a flat piece of metal with a reduced portion 6 at one of its ends. Arranged centrally of the reduced portion 60 and extending longitudinally for its entire length are a pair of spaced upwardly extending flanges 7 between which are formed a plurality of notches 8 the purpose of which will be set forth later. The main portion 65 of the base member 5 is provided with transversely extending ribs 9 and 10 at each end. Rigidly attached to the rib 9 is a substantially U shaped bearing 11 which supports the upright standard 12 pivotally secured thereto through the medium of the transversely extending bolt 13. This standard is of a rectangular configuration and is slotted longitudinally through its face for approximately 70 its entire length, as clearly shown 75 in Figure 3. The two outer faces of the side pieces of the standard 12 are provided with a plurality of ratchet teeth 15. The rib 10 rigidly supports at each of its ends a bearing block 16 which is more clearly 80 illustrated in Figure 9. The outer side of the bearing blocks are arcuate in shape and recessed as at 17. A vertically extending bar 18 is mounted between the bearing blocks 16 being pivotally connected thereto by the 85 pivot pin 19, the ends of which are disposed within the recess portions 17 of the bearing blocks. The bar 18 is of the same length as the standard 12 and has its inner face 90 also provided with ratchet teeth 20. The 90 lower edge of the standard 12 is beveled as at 21 which limits the rearward movement of this member. Pivotally connected to one side of the bar 18 is the brace lever 22 which extends between the bar and the standard 95 having its free end disposed in the recess 23 formed in one edge of the standard. This lever holds the members in spaced relation, as clearly shown in Figure 1. In order that the bar 18 may be supported in a vertical 100 position, a support 24 is pivotally connected to the bar approximately intermediate its length, as at 25. The lower end of the support 24 is beveled as at 26, and is adapted to engage the notches 8 which regulate the 105 adjustment of the lever 18.

The lifting lever 27 passes through the slot 14 in the standard 12 within close proximity to the ratchet teeth 20 of the bar 18. The outer end of the lever 27 is slightly 110 offset as at 28, to form the handle 29. The portion of the lever which is disposed be-

tween the standard 12 and the bar 18 is enlarged, as at 30 with each of its sides provided with an upwardly tapering groove or recess 31. The lower front portion of the 5 enlargement 30 is slotted as at 32, to receive the spring actuated pawl or lug 33. This lug is of a substantial rectangular shape having at one end two outwardly turned projections 34. The central portion of the pawl 10 is grooved as at 35, to receive the coil spring 36 which normally holds the pawl in an extended position and in engagement with the ratchet teeth 20 of the bar 18. A hook 37 of a substantial Y shape has its upper 15 ends 38 bent inwardly and pivotally connected to the enlargement 30 above the slot 32. The sides of the hooks extend downwardly past the pawls 33 and engage the outwardly extending projection 34, as 20 clearly shown in Figure 7. The lower end or stem of the hook is provided with an eyelet 39 to which is loosely attached a longitudinally extending rod 40 which passes beneath the lifting lever 27 and through the 25 slot 14 to a position directly beneath the offset portion 28 of the lever 27. In order that the rod 40 will be supported in a substantial horizontal position, a bearing 41 is formed from a piece of wire coiled intermediate its 30 length as at 42, and extending upwardly so that its ends 43 may be joined to the lever 27. The outer end of the rod 40 is looped providing a finger engaging loop 40'.

Disposed longitudinally beneath the center of the lifting lever 27 is a U shaped bracket 44 which is fixedly secured thereto by bolts or other suitable means. This bracket is so positioned that the transversely extending opening left by the bracket will 40 be on a plane with the outer or ratchet surface of the upwardly extending standard 12. Slidably mounted in this opening is a pawl 45 having a centrally projecting portion 46 which is disposed within the slot 14 of the standard 12 to regulate the lateral movement of the pawl. The opposite side of the pawl is recessed at its center to receive the coil spring 47 which normally holds said pawl in engagement with the ratchet 45 teeth 15 of the standard 12. This pawl is actuated by the lever 48 which is bent intermediate its length extending along the side of the lever 27 until its ends engage the openings 49 at each side of the pawl 45.

55 A shoe 50 of arcuate shape is adapted to engage beneath the axle of the vehicle preparatory to the operation of the jack. This shoe is provided with a downwardly extending shank 51 which is slotted for approximately its entire length to receive that portion of the enlargement 30 which separates the grooves or recesses 31. Each side of the shank 51 is provided with spaced key hole openings 52 that are in alignment with 60 each other and adapted to receive the key

53 which regulates the adjustment of the shoe. The tapering shape of the groove 31 permits slight swinging movement of the shank 51 which is desirable.

In use, the standard 12 is raised to a vertical position followed by the raising of the bar 18 which is spaced from the standard 12 through the medium of the brace bar 22. The bar 18 is adjusted by the support 24, the lower end of which engages the notches 8 formed in the extension 6 of the base member 5. The enlarged portion 30 of the lifting lever is then passed through the vertically extending slot 14 in the standard 12 so that the pawl 33 is normally in engagement with the ratchet teeth 20 of the bar 18. When in this position the pawl 45 will be in engagement with the ratchet teeth 15 of the standard 12. The shank 51 of the shoe 50 is then slipped over the portion of the enlargement which separates the grooves 31 and is adjusted in its desired position by the key 53. When in this position the jack 51 is ready for use. However, in assembling the device it is necessary to place the jack 90 beneath the axle of the vehicle before the bar 18 is raised into position. The shoe 51 is then placed directly beneath the axle and by applying pressure to the handle 29 the pawl 33 will be moved upwardly a notch, 95 the pawl 45 acting as a fulcrum in this movement. The handle 29 is then pulled upwardly, during which movement the pawl 45 will be moved two notches. This movement is continued until the axle of the vehicle has been raised sufficiently for the purpose desired. To release the jack the levers 40 and 48 are alternately pulled outwardly so as to disengage the pawls from the ratchet teeth, thus lowering the jack slowly. When 100 not in use, the device may be collapsed into a very small compass so as to be conveniently carried from place to place.

It is to be understood that the form of my invention herewith shown and described, 110 is to be taken as a preferred example of the same, and that certain changes in the shape, size, and arrangement of parts may be resorted to without departing from the spirit of the invention or the scope of the subjoined claims.

Having thus fully described my invention, I claim:

1. A device of the class described comprising a base member, upright standards 120 pivotally associated with said base, ratchet teeth formed on the edges of the standards, a lifting lever passing through a slot in one of the standards, an enlarged portion formed on the lever intermediate the standards, downwardly tapering grooves on opposite sides of the enlarged portion, a shoe having a depending shank, a slot formed in the shank for receiving that portion of the enlargement which separates the said 130

grooves, and means carried by the shank for adjusting the shoe.

2. A lifting jack comprising a base member, an upright standard pivotally connected to the base and slotted longitudinally, a ratchet bar pivoted to the base in spaced relation to said standard, a lever passing through the slotted standard having an enlarged end in close relation to said bar, a 10 spring actuated pawl mounted within a slot in the end of the lever engageable with the ratchet bar, a second pawl mounted upon the lever approximately midway its length, said pawl adapted to engage ratchet teeth 15 formed upon the sides of the standard, and rods for controlling the actuation of the pawls.
3. A lifting jack comprising a base member, a slotted standard pivotally connected

thereto, a bar spaced from said standard in alignment with the slot, a lever extending through the slot in the standard, said lever having an enlarged end between the standard and bar, ratchet teeth formed on the said standard and bar, pawls slidably mounted upon the lever engageable with the ratchet teeth, rods for actuating the pawls, 20 grooves on the sides of the enlarged end of the lever, a shoe having a bifurcated shank fitting the said grooves, and means permitting vertical adjustment of the shank with respect to the lever.

In testimony whereof, I have affixed my signature in the presence of two witnesses.

AARON L. MANN.
